(57) **CLAIM**

The ornamental design for a wrist weight, as shown and described.

DESCRIPTION

FIG. 1 is a perspective bottom view of a wrist weight showing my new design in an open unwrapped condition resting on a flat surface;

FIG. 2 is a perspective top view of the wrist weight of FIG. 1; FIG. 3 is a bottom plan view of the wrist weight of FIG. 1; FIG. 4 is a top plan view of the wrist weight of FIG. 1; FIG. 5 is a left side view of the wrist weight of FIG. 4; FIG. 6 is a right side view of the wrist weight of FIG. 4; FIG. 7 is a front view of the wrist weight of FIG. 4; FIG. 8 is a rear view of the wrist weight of FIG. 4; FIG. 9 is a perspective view of a wrist weight in an open unwrapped condition wherein a user's arm is inserted through the weight; and, FIG. 10 is a perspective view of a wrist weight in a wrapped closed condition. The dashed lines on the surface of the wrist weight represent stitching. The remaining dot-dashed lines, which represent a user's arm, illustrate environment structure and form no part of the claimed design.
